UNITED STATES PATENT OFFICE.

CHARLES M. KELLOGG, OF DOBBS FERRY, NEW YORK, ASSIGNOR TO THE
ADHESIVE GIMP COMPANY, LIMITED, OF NEW YORK, N. Y.

DESIGN FOR GIMP.

SPECIFICATION forming part of Design No. 27,048, dated May 11, 1897.

Application filed January 15, 1897. Serial No. 619,372. Term of patent 3¹ years.

To all whom it may concern:

Be it known that I, CHARLES M. KELLOGG, of Dobbs Ferry, county of Westchester, and State of New York, have invented and produced a new and original Design for Gimp, of which the following is a specification, reference being had to the accompanying drawing, forming part thereof.

The said drawing illustrates a face view of a piece of gimp showing my design, which consists of the lays *a* and *b*, having pointed ornamental figures and arranged adjacent to the edges of the gimp longitudinally thereof,

the two longitudinal cords *c* and *d*, arranged equidistant from the middle of the gimp and having the bars *e* crossing the same transversely, and the rectangular longitudinal lay *f*, arranged at the middle of the gimp and having the bars *g* crossing the same transversely.

What I claim is—

The design for gimp substantially as herein shown and described.

CHARLES M. KELLOGG.
